VENETIAN BLIND

Glenn L. Sherwood, Benton Harbor, Mich., assignor to Kaywood Corporation, Benton Harbor, Mich., a corporation of Michigan

Application December 13, 1941, Serial No. 422,788

9 Claims. (Cl. 160—176)

This invention relates to an improved Venetian blind construction. More particularly, it relates to a Venetian blind having an improved head box structure.

It is an object of this invention to provide a Venetian blind having a brake of improved design for the tilting mechanism.

A further object is to provide a Venetian blind having a brake on the tilting mechanism which is released by pulling on either cord operating the tilting mechanism and is reapplied automatically when said pull is released.

Another object is to provide a Venetian blind structure in which the tilting mechanism includes a novel drum and associated gear train.

Other objects will appear hereinafter.

It has now been found that the foregoing objects are accomplished by providing the structure shown in the attached drawings which form a part of this specification and in which

Figure 1 is a front elevation of a Venetian blind embodying the features of the present invention;

Figure 2 is an enlarged vertical section on the line 2—2 in Figure 1;

Figure 3 is an enlarged view in perspective of the head box of the blind shown in Figure 1, with a portion of the head box casing lifted away to reveal the arrangement of parts in the head box;

Figure 4 is an enlarged view partly in vertical section approximately on the line 4—4 in Figure 3;

Figure 5 is a vertical section on the line 5—5 in Figure 4;

Figure 6 is a view similar to Figure 5 but showing the mechanism in another position;

Figure 7 is an enlarged view in perspective of the winding drum for the tilting mechanism;

Figure 8 is an enlarged view in perspective of the principal parts of the brake for the tilting mechanism;

Figure 9 is an enlarged vertical section on the line 9—9 in Figure 3;

Figure 10 is a vertical section on the line 10—10 in Figure 9;

Figure 11 is an exploded view in perspective of the housings for a portion of the tilting mechanism; and

Figure 12 is an exploded view in perspective of one of the rocking arms of the tilting mechanism and of a support for one of the guide rolls for one of the lifting ropes.

Figure 1 shows a Venetian blind, designated generally 20, having a head box 22, the details of which are more fully illustrated in the other figures. The usual pair of tapes 24 depend from the

head box 22 and support slats 26 in the conventional manner by smaller tapes 28, as shown more particularly in Figure 2. Each tape 24 extends from the head box 22 downwardly underneath the heavy lower slat 30, and thence upwardly again into the head box so that both free ends of each tape are located in the head box 22. As is common in Venetian blind constructions, the tapes 24 serve not only to support the slats 26 in spaced relation but also to tilt the slats 26 in one direction or the other when they are operated on by the tilting mechanism described hereinafter.

The head box 22, as is shown clearly in Figures 2 and 3, is provided with a casing including a pair of longitudinally extending, generally L-shaped members 32 and 34. As may be seen, the casing member 34 is provided with flanges 36 and 38 along its longitudinally extending free edges which cooperate with the edges of the casing member 32. The ends of the longitudinally extending, hollow casing formed by members 32 and 34 are closed by brackets 40 which are similar in construction although complementary to each other rather than identical. They are described together because of their functional identity but it will be understood that one is a right-hand bracket and the other a left, and that they are not interchangeable.

In Figure 3 the head box 22 is shown with the casing member 32 removed in order that the arrangement and location of the parts therewithin may be readily seen. Near the left-hand end of the head box 22, as shown in this figure, a gear housing 72 is secured to the bottom portion of the casing member 34 by suitable fastening means, such as, for example, self-tapping screws 14 extending up through an opening in the member 34 and threaded into a flange 76 provided on gear housing 72. As best seen in Figures 4 and 11, gear housing 72 includes a vertically-extending plate 78, on the lower edge of which the flange 76 is formed. The remainder of the gear housing 72 is provided by another plate including a vertically-extending portion 80, a horizontally-extending portion 82 forming the top of the gear housing, and a downwardly-extending flange portion 84 which is secured to the plate 78 by a suitable means such as, for example, welding.

The wall 80 of gear housing 72, in cooperation with generally L-shaped, sheet metal member 86, forms another housing 88. As may be seen in Figure 4, the horizontal portion of the L-shaped member 86 overlies the top 82 of the gear hous-

ing 72 and is secured thereto by any suitable means, such as self-tapping screws 90.

Rotatably mounted within the housing 88 is a drum 92 which forms a portion of the tilting mechanism. The drum 92 is formed by a pair of complementary members 94 and 96 presenting generally cylindrical surfaces 98 and 100 and provided with annular flanges 102 and 104 on their outer ends. At the inner ends of the cylindrical portions 98 and 100 the sheet metal forming the portions 94 and 96 extends inwardly towards the axis of the drum 92, thence obliquely downwardly and outwardly toward portions 106 and 108 forming hubs for the drum 92. By forming the drum of sheet metal shaped as shown and described, the drum is given sufficient size and strength and at the same time is kept relatively light, thus contributing to keeping down the over-all weight of the blind 20. The members 94 and 96 may be secured together by spot-welding, for example, at two or more points about the abutting inturned portions of members 94 and 96.

Extending through square openings in the hubs 106 and 108 axially of the drum 92 is a square shaft 110 having a bushing 112 die-cast on one end and another bushing 114 driven onto the other end. A portion of shaft 110 projects outwardly beyond bushing 114 and is riveted over, thereby securing bushing 114 on the shaft and also securing the two halves 94 and 96 of the drum together centrally. The annular groove 115 and complementary die-cast rib 117 secure bushing 114 and shaft 110 against relative axial displacement. As will be apparent, the drum 92 and bushings 112 and 114 all turn with shaft 110, bushings 112 and 114 serving as bearings for the assembly. These bushings 112 and 114 are respectively received in openings 116 and 118 formed in the vertical wall 80 and the vertical portion of L-shaped member 86. Bushing 114 is provided with an annular rib 120 which serves to position the drum centrally within the housing 88. The bushing 112 has formed integrally therewith on its outer end a gear 122 which projects into the gear housing 72.

Also mounted within the housing 88 is a brake structure consisting of a brake member 126 and a spring member 128 pivotally mounted upon a pivot pin 130, the opposite ends of which are supported in openings provided in wall 80 and in the vertical portion of housing member 86. The brake member 126 and spring member 128 are shown in perspective in Figure 8. The brake member 126 includes a generally flat, rectangular body portion 131 provided at its rear end with an upwardly extending flange 132. The brake member 126, forwardly of the generally flat body 131, curves downwardly and terminates in a guide member 134 formed by turning inwardly portions of the stock from which the brake member 126 is formed. This guide member 134 narrows gradually from the inner end toward the outer end. The free inner edge 136 of the guide member 134 and the bottom 138 and sides 140 of the outer edge are flared outwardly as shown to avoid wear on the tilting ropes 142 and 144 which extend through this guide member 134, as shown in Figures 5 and 6.

Generally centrally of the rear of the brake member 126 an opening 146 is provided which extends into both the body portion 131 and the flange 132. The spring member 128 is formed of a relatively long narrow strip of suitable thin

metallic material bent upwardly at its rear end, as at 148, and then laterally, as at 150.

In assembling the brake structure 124 the spring member 128 is positioned with the portions 148 and 150 extending in the opening 146 in the brake member 126 and with the pivot pin 130 positioned between the spring member 128 and the brake member 126, as is clearly shown in both Figures 5 and 6. The body portion 152 of spring member 128 then extends underneath the body of brake member 126 and outwardly beyond the downwardly curved portion thereof, terminating under the guide portion 134.

Also, as shown in Figures 5 and 6, the brake member 126 and the spring member 128 extend outside the housing of the head box 22 through an opening 154 provided in the bottom portion of casing member 34 adjacent the forward edge thereof. The effective size of this opening is further increased by deforming the flange 36 outwardly, as at 156, adjacent the opening 154 (see Figures 3 and 5). The deformation at 156 is made great enough and the opening at 154 large enough to permit the brake member 126 to pivot through a small angle about the pivot 130, and the brake structure 124 is so arranged that the body portion 131 of the brake member 126 may pivot upwardly far enough to press with appreciable force against the tilting cords 142 and 144 wound on the drum 92 between the flanges 102 and 104 which serve to retain them on the drum 92. As shown in Figure 5, the brake member 126 is arranged so that the cords 142 and 144 are pressed between the body 131 and the cylindrical surface of the drum 92 at 158 when the brake member is in its uppermost position, as shown in Figure 5. It will also be observed that the rear edge of opening 154 is engaged by the spring member 128, which latter is thus put under tension and in turn tends at all times to force brake member 126 upwardly toward the drum 92, as is illustrated in Figures 5 and 6.

The drum 92, which operates the tilting mechanism in the manner hereinafter described, is itself operated by the tilting cords 142 and 144 above referred to. A circular opening 160 through the cylindrical surface of drum 92 is provided adjacent each of the flanges 102 and 104. The upper ends of the tilting cords 142 and 144 are each extended through these openings 160 and knotted or otherwise secured interiorly of drum 92, as shown at 164 in Figure 4. As is indicated in Figures 4 and 7, the cords 142 and 144 are then wound about the cylindrical surface of drum 92 in opposite directions and in a single layer progressing inwardly toward the center until they meet, a substantially equal length of each of the cords being wound about the drum. The free ends of cords 142 and 144 extend from the drum through the guide member 134 and outwardly of the head box 22. As shown in Figure 1, the free ends of cords 142 and 144 then hang downwardly in front of the slats 26, terminating at a point where they are conveniently accessible and being provided with grips 166 on their lower ends.

To assist in retaining the cords 142 and 144 in place on the drum 92, a guard 168 is provided which extends across in front of drum 92. The portion 170 of guard 168 extending in front of drum 92 is curved vertically, as best seen in Figures 5 and 6. An inturned portion 172 is provided on the right-hand end of the guard which lies along the vertical wall 80 and is secured

thereto as, for example, by welding, to support the guard 168 in place.

The drum 92 drives the main shaft 174 of the tilting mechanism through a reducing gear train located within the housing 72 adjacent the drum housing 88. The gear 122, which is integral with bushing 112 and turns with the drum 92, has already been referred to above. This gear 122 meshes with and turns a larger gear 176 which is formed integral with another small gear 178, as, for example, by die-casting the two as a unit. The integral gears 176 and 178 are mounted on a pin 180, which is provided with a round head 182 and is in turn supported in a pair of aligned openings in walls 78 and 80. Pin 180 is positioned with its round head 182 located in drum housing 88 and, as indicated in Figure 5, flange 102 extends over head 182 sufficiently to prevent dislodgement of pin 180 so long as drum 92 is in place. A small boss 184, also formed integral with gears 176 and 178, extends axially out beyond the end face of gear 176 and serves to space gear 176 from wall 80. The small gear 178 in turn drives a large gear 186 which is preferably an integral part of a bushing 188 which may also be formed by die-casting.

The bushing 188 is mounted to rotate in an opening 190 formed in the wall 78 which serves as a bearing therefor. A portion of the bushing 188 extends outside the gear housing and is drilled, as at 192, to receive a cotter-pin 194. The cotter-pin 194 extends through the square shaft 174 and secures the latter in the square opening 196 formed in the bushing 188 so that the shaft 174 turns with the bushing 188. Shaft 174 is, however, freely received within the opening 196 and when the cotter-pin 194 is withdrawn the shaft 174 may then be readily removed. The amount of reduction accomplished in the gear train just described may vary, as desired. It has been found, however, that satisfactory results are obtained if the gears 122 and 178 each have eight teeth, and the gears 176 and 188 each have twenty-four teeth, giving a reduction of six to one.

The end of shaft 174 opposite that supported through the bushing 188 is journaled in a circular opening 198 formed in vertically extending panel 200 having a flange 202 formed on the bottom thereof. The panel 200 is secured in place by fastening units, such as self-tapping screws 204, extending upwardly through the lower wall of casing member 34 and threaded into the flange 202.

Mounted on the square shaft 174 between the bushing 188 and the panel 200 is a pair of tilting frames 206. The number of these frames may be increased where the blind is fairly wide and additional tapes are necessary to adequately support the slats. As is best seen in Figure 15, these frames include a generally square base 208 provided with vertically extending flanges 210, 212, 214 and 216. A generally square opening 218 is provided centrally in the base for a purpose which will become more apparent herein-after.

Centrally of the flanges 210 and 214 adjacent the base 208 opposite square openings 220 and 222 are provided through which shaft 174 extends. The openings 220 and 222 are just large enough to receive the shaft 174 and accordingly the frames 206 turn with the shaft 174. On either side of the shaft 174 adjacent the flanges 210 and 214 the edges of the opening 218 are struck up, as at 224, for strengthening purposes.

As may be seen in Figures 2 and 3, the opposite ends of each tape 24 are secured to the opposite sides of a tilting frame 206. To this end the extremities of the tape are folded back upon themselves, as is clearly shown in Figure 2 at 226, and the folded portions are secured together with staples 228 (Figure 3) or by any other means, thereby providing a loop 230 through which a pin 232 is extended, the ends of which are received in a pair of openings 234, one of which is formed in each of flanges 210 and 214. The opposite ends of the pins 232 extending through the openings 234 are bent in toward the flanges 210 and 214, thereby securing the pins in place. As may be seen in Figure 2, the tapes extend into the frame 206 over the flanges 212 and 216, thereby decreasing the pull exerted on the pins 232. Openings 235 are provided in the horizontal portion of casing member 34 adjacent the front and rear edges thereof underneath each of the tilting frames 206 to provide means for the tapes 24 to extend into the head box 22.

Also supported on the shaft 174 is a pair of saddles 236 (the number may be varied, as desired, as will appear hereinafter). These saddles 236 are not arranged to rotate with the shaft 174 but instead are intended to remain relatively stationary as the shaft is turned. As best seen in Figure 12, the saddles 236 are provided with a curved upper portion 238 through which the shaft extends and which permits them to remain relatively stationary as the shaft is turned. Below this curved portion the saddles flare outwardly on either side, as at 240, below which relatively straight side portions 242 are provided, the bottoms of which curve slightly outwardly. Adjacent the right-hand end of each saddle member 236 a pair of oppositely disposed openings 244 is provided in the relatively straight portions 242. Extending through these openings a shaft 246 is provided with a head 248 on one end and riveted over on the other end at 250, thereby securing it in place. Rotatably mounted on this shaft 246 between the vertical sides 242 of the saddle 236 is a pulley 252. The purpose of the opening 218 in the tilting frame 206 is now apparent. As may be seen in Figures 2 and 9, the saddle 236 extends down through this opening. The opening is wide enough so that the frames 206 may be tilted to a substantial angle without bringing the front or rear edge of the opening 218 into contact with the saddle 236.

To raise and lower the blind 20 a pair of lifting cords 254 and 256 is provided. To render these cords as inconspicuous as possible they are preferably centered with respect to tapes 24. To this end an opening 258 is formed in the heavy lower slat 30 midway between the edges of each tape 24 where the tape passes around the lower slat 30. As clearly shown in Figure 2, each opening 258 is enlarged at its lower end, as at 260, this enlarged lower end being covered over by the tape 24 in the completed structure.

The lifting cords 254 and 256 extend down into the openings 258 and are knotted on their lower ends, as at 262, the knots being positioned in the large lower opening and engaging the shoulders provided by the reduced diameter of the upper portion 258. As is apparent, by this means the cords 254 and 256 when pulled up raise the heavy lower slat 30 and ultimately the whole slat structure of the Venetian blind.

Vertically above the opening 258 openings 264 are provided in each of the slats 26, and the tapes

254 and 256 extend up through these openings 264, thence through openings 266 in the horizontal portion of casing member 34, and over the guide pulleys 252, as indicated in Figures 2, 4 and 9.

Returning again to the lifting cords 254 and 256, it will be seen that cord 256, after passing over its guide pulley 252, extends to the right over the second guide pulley 252 where it joins cord 254. Both cords then pass through an opening 272 formed in the panel 200. Carried on the right-hand face of panel 200 in alignment with the opening 272 is housing 274 through which the lifting cords 254 and 256 are guided and in which a locking pawl assembly is provided which serves as a releasable brake for the lifting cords.

As shown in Figure 10 the lower end of the housing 274 extends outwardly of the head box 22 through an opening 286 provided adjacent the forward edge of the horizontal portion of casing member 34, the metal forming the flange 36 being deformed, as at 288, to permit the housing 274 to extend forwardly with respect to head box 22. The extreme lower end of the housing 274 is also curved outwardly, as at 290, to avoid wear on the lifting cords 254 and 256 and to give a more pleasing appearance.

Below the housing 274 the two cords 254 and 256 are joined together and in reality constitute a single cord, as indicated at 310 in Figure 1. To hold the cords 254 and 256 together between the point where they join at 310 and the housing 274, a buckle-like member 312 is provided which has a central opening 314 divided into two parts by a bar 316. The cords pass into the buckle-like member 312 through one-half of the opening 314, thence over the bar and out the other half, leaving on the same side on which they enter in the usual manner.

The blind is tilted by operating the cords 142 and 144. Depending on which of these cords is pulled, the drum 92 rotates in one direction or the other, and through the gears in housing 72 turns shaft 174 in a corresponding direction. The one cord is wound on drum 92 as the other is unwound so that the drum is readily adjusted to any desired position. It may be readily observed, particularly in Figures 2, 5 and 6, that any downward pull on either cord 142 or 144 will also pull down brake 126, drawing it away from cords 142 and 144 on drum 92, and that upon release of the pull the brake 126 will be returned to braking by the action of spring 128. As shaft 174 turns one side of each tilting frame 206 will be raised and the other lowered, thus raising one end of each tape 24 and lowering the other, tilting slats 26 in the usual manner.

There are many advantages and improved features embodied in the Venetian blind which forms the subject of this invention. The brake structure is new and decidedly advantageous, for example. The arrangement by which the brake is released and applied by any normal pull on the tilting cords to tilt the blind is a distinct improvement over structures heretofore known. The application of the brake member to the cords on the drum gives an extensive braking surface, and the lack of any necessity for pulling the cords in a particular manner or taking any other action to release the brake is a distinct improvement. The brake structure is at the same time extremely simple and involves a combining of functions in a single part since the brake member also serves as a guide for the tilting cords.

Other advantages will be apparent from the foregoing description. Suitable materials of construction may be readily selected by those skilled in the art. The blind is particularly designed to be fabricated largely of metal, particularly sheet metal, thereby providing strength, lightness and simplicity.

It is apparent that many widely different embodiments of this invention may be made without departing from the spirit and scope thereof, and therefore it is not intended to be limited except as indicated in the appended claims.

The invention is hereby claimed as follows:

1. A Venetian blind structure comprising in combination means for tilting the blind including actuating means, means for normally braking said tilting means, and means operated by movement of said actuating means to tilt said blind for releasing said braking means.

2. A Venetian blind structure comprising in combination means for tilting the blind, pivotally mounted brake means resiliently urged about its pivot point radially inwardly against a rotatable portion of said tilting means and means actuated by a pull on said cord for releasing said brake means.

3. A Venetian blind structure comprising in combination means for tilting the blind, including a drum about which a tilting cord is wound, and pivotally mounted brake means resiliently urged about its pivot point to press the rope against said drum, and means for shifting said brake means away from said drum to release said cord, said means being actuated by the pull necessarily exerted on the tilting cord during the tilting of the blind, and said brake means returning to braking position upon release of said pull.

4. A Venetian blind structure comprising in combination means for tilting the blind, including a drum about which tilting cords are oppositely wound and to which one end of each of said cords is secured, and pivotally mounted brake means extending beneath said drum and resiliently urged about its pivot radially inwardly against said cords on said drum, said brake means being engaged by the tilting cords extending from said drum downwardly whereby a pull on either cord shifts said brake means away from the cords on said drum thereby releasing the brake, and whereby said brake means returns to braking position upon release of said pull.

5. A Venetian blind structure comprising in combination means for tilting the blind, including a drum about which tilting cords are oppositely wound and to which one end of each of said cords is secured, a pivotally mounted brake member having an extensive braking surface extending beneath said drum and underlying a plurality of turns of said cords on said drum, and means resiliently urging said brake member about its pivot radially inwardly against said cords on said drum, said braking member being pivotally mounted rearwardly of the axis of said drum and extending forwardly of said drum, and said cords extending outwardly from said drum and downwardly over the forward edge of said brake member whereby a pull on either pivot of said brake means away from the cords on said drum releasing the brake, and whereby said brake means returns to braking position upon release of said pull.

6. A Venetian blind structure comprising in

combination means for tilting the blind, including a drum about which tilting cords are oppositely wound and to which one end of each of said cords is secured, a pivotally mounted brake member having an extensive braking surface extending beneath said drum and underlying a plurality of turns of said cords on said drum, and means resiliently urging said brake member about its pivot radially inwardly against said cords on said drum, said braking member being pivotally mounted rearwardly of the axis of said drum and extending forwardly of said drum, and said cords extending outwardly from said drum and downwardly over the forward edge of said brake member through a guide formed on the upper surface of said brake member adjacent said forward edge, whereby a pull on either pivots said brake means away from the cords on said drum releasing the brake, and whereby said brake means returns to braking position upon release of said pull.

7. A Venetian blind structure comprising means for tilting the blind, a head box, including a drum rotatably mounted in said head box on a horizontal axis extending longitudinally thereof and about which drum tilting cords are oppositely wound and to which one end of each of said cords is secured, a brake member pivotally mounted on an axis parallel to said drum axis and having an extensive braking surface extending beneath said drum and underlying a plurality of turns of said cords on said drum, and means resiliently urging said brake member about its pivot radially inwardly against said cords on said drum, said pivot for said brake member being located below and to the rear of said drum axis, said brake extending forwardly of said drum adjacent the lower front edge of said head box, and said cords extending forwardly from said drum and downwardly out of said head box over the forward edge of said brake member through guide means formed on the top surface of the forward end of said brake member whereby a pull on either pivots said brake means away from the cords on said drum releasing the brake, and whereby said brake means returns to braking position upon release of said pull.

8. A Venetian blind structure comprising in combination, a head box, slat tilting means therein including a longitudinally supported shaft mounted for rotation in said head box, means for turning said shaft comprising a drum rotat-

ably mounted in said head box at one end thereof, tilting cords reversely wound upon and attached to said drum, said cords depending from said head box in position to be pulled to turn said shaft, said drum comprising a sheet metal rim portion having integral radially extending webs, spaced bearings secured to said webs, a relatively short shaft mounted in said bearings and turnable therewith, one of said bearings having a lateral extension provided with integral gear teeth, said longitudinal shaft having a bushing affixed to one end thereof, said bushing including a toothed portion and intermeshing reducing gearing between said toothed portion and the teeth on said first mentioned shaft.

9. In a Venetian blind structure in combination with a head box and slat tilting mechanism mounted thereon including a rotatable shaft mounted in said head box for tilting said slat tilting mechanism, a drum turnably mounted in said head box, said drum comprising a pair of complementary members having cylindrical surfaces and provided with annular flanges at their outer ends, the inner ends of the cylindrical surfaces being formed of sheet metal and having portions extending inwardly toward the axis of the drum thence obliquely radially inwardly to form hub portions for the drum, said complementary members being spot welded together in abutting relationship, said hub portions having polygonal openings and a polygonal shaped shaft in said openings and provided with a bushing die cast on one end thereof, the opposite end of said shaft having a bushing, supporting means in the box for supporting said bushings, means on said die cast bushing and said shaft for securing the same against relative axial displacement, said die cast bushing having integrally formed therewith on its outer end a gear extending adjacent but spaced from the end of said longitudinal shaft, a second bushing on said adjacent end of said longitudinal shaft, said bushing having gear teeth thereon and gearing intermeshing with said gear teeth and the gear on the drum shaft, said cylindrical sheet metal portion of said drum having openings therein and a pair of cords reversely wound on said drum with their inner ends passing through said openings, said cords having means for holding said ends from detachment from said openings, said cords passing outwardly through said head box.

GLENN L. SHERWOOD.
